[57] **CLAIM**

The ornamental design for a telephone network interface apparatus, as shown and described.

DESCRIPTION

FIG. 1 is a front elevational view of a telephone network interface apparatus showing our new design in closed condition;

FIGS. 2 and 3 are respectively top and bottom plan views thereof;

FIGS. 4 and 5 are respectively left and right side elevational views thereof;

FIG. 6 is a rear elevational view thereof; and

FIG. 7 is a fragmentary front elevational view showing the upper portion of the doors in opened position.

FIG.1

FIG.5

FIG.3

FIG.2

FIG. 4

FIG. 6

FIG. 7
